DESIGN FOR A FOUNTAIN PEN

John Vassos, Silver Mine, Conn., assignor to L. E. Waterman Company, Newark, N. J., a corporation of New York

Application December 16, 1939, Serial No. 88,940

Term of patent 14 years

To all whom it may concern:

Be it known that I, John Vassos, a citizen of the United States, residing at Silver Mine, in the county of Fairfield and State of Connecticut, have invented a new, original, and ornamental Design for Fountain Pen, of which the following is a specification, reference being had to the accompanying drawing, forming a part thereof.

I claim:

The ornamental design for a fountain pen, substantially as shown.

JOHN VASSOS.
